(57) **CLAIM**

The ornamental design for a solar powered water quality raft as shown and described.

DESCRIPTION

FIG. 1 is an isometric top view of a solar powered water quality raft in a first configuration.

FIG. 2 is an isometric top view of the solar powered water quality raft in a second configuration with one solar panel lifted showing access to the interior.

FIG. 3 is an isometric bottom view of the solar powered water quality raft in said first configuration.

FIG. 4 is a front view thereof.

FIG. 5 is a rear view thereof.

FIG. 6 is a right side view thereof.

FIG. 7 is a left side view thereof.

FIG. 8 is a top side view thereof; and,

FIG. 9 is a bottom side view thereof.

The broken lines in the figures are for the purpose of illustrating portions of the solar powered water quality raft that form no part of the claimed design.
